CIGAR AND CIGARETTE EXTINGUISHER

Zeno Carl Manning, San Francisco, Calif.

Application September 1, 1948, Serial No. 47,198

15 Claims. (Cl. 131—235)

1

This invention relates to a cigar and cigarette extinguisher and has for one of its objects the provision of a simple, sanitary and highly efficient means for quickly extinguishing burning cigar and cigarette butts and for ejecting such butts from the extinguisher and into a receptacle adapted to support said extinguisher without tilting or otherwise moving the receptacle.

Another object of the invention is the provision of an extinguisher comprising a plurality of upstanding pins on which the cigar and cigarette butts are adapted to be impaled during extinguishment, and which pins have a stripper device associated therewith whereby said pins and stripper device are adapted to move relatively for stripping the said butts off said pins and for automatically ejecting or discharging such butts to one side of said pins for falling into a receptacle therefor.

Heretofore, as disclosed in United States Letter Patent No. 1,999,245 of Robert D. Mackenzie dated April 30, 1935, it has been old to provide impaling pins for cigar and cigarette butts with reciprocatory means for sliding the impaled butts off the pins. However, once the butts are off the pins, in devices of this kind, they tend to fall back on top of the pins and unless the extinguisher is shaken or tilted, the butts interfere with the extinguishment of subsequent cigars or cigarettes. Furthermore, the devices of this general character have heretofore been difficult to keep clean inasmuch as the ashes falling from the butts tend to become lodged about the bases of the pins, thereby preventing the reseating of the stripper, and also it is practically impossible to clean the area about the bases of the pins.

One of the objects of the present invention is the provision of improved means for overcoming said objections.

In the drawings, Fig. 1 is a vertical sectional view taken through an ash and butt receptacle that includes the improved extinguisher. This view is taken along line 1—1 of Fig. 2.

Fig. 2 is a plan view of the device of Fig. 1.

Fig. 3 is a sectional view taken through a table model receptacle showing a slightly modified form of the invention. The extinguisher per se is shown in elevation in this view.

Fig. 4 is a plan view of a still further form of the invention that is slightly different from the forms illustrated in Figs. 1 to 3.

Fig. 5 is a side elevational view of the device of Fig. 4.

In detail, referring to Figs. 1, 2, the invention

2

as illustrated is shown in position within a conventional ash and butt receptacle 1 of the type used in automobiles. These receptacles as used in automobiles and other vehicles are for the most part somewhat similar and have side walls 2 (Fig. 1) and a bottom wall 3. The top is open and the receptacle is adapted to be moved through an opening in a panel from a concealed position to an exposed position. The details of how the receptacle is mounted are immaterial to the present invention.

The extinguisher comprises a base member or plate 4 (Fig. 1) to which the lower ends of a plurality of vertically extending spaced pins 5 are secured. The pointed ends of said pins are uppermost and are exposed for impaling a cigar or cigarette butt 6 thereon.

In Fig. 2 several parallel rows of the pins are shown as extending at right angles to the wall 2 to which the plate 4 is secured. Said plate 4 is horizontal and may have a downwardly projecting flange 7 thereon that may be screwed or spot welded to wall 2, although it is obvious that the said plate 4 could be struck out from wall 2 in certain instances, thus eliminating flange 7.

The pins 5 may be secured to plate 4 in any suitable manner and the edge of said plate remote from the wall 2 may have aligned extensions 8 at the opposite ends of said edge.

Above plate 4 is a stripper plate 9 a portion of which is similar in outline and size to plate 4 therebelow, the said plate 4 may be rectangular in shape. Stripper plate 9 may have ears 10 that extend under and partially around the laterally outwardly projecting aligned extensions 8 for pivoting the stripper plate 9 to base plate 4, for swinging of the stripper plate about the common axis of extensions 8, the latter being along the edge of plate 4 that is remote from side wall 2 and constituting hinge pins.

Stripper plate 9 is formed with parallel slots 11 (Fig. 2) that extend from positions adjacent the pivoted edge of plate 9 toward wall 2, there being a slot adapted to surround each row of pins 5.

The stripper plate 9 has a portion 12 (Fig. 1) perpendicular to said plate that extends upwardly along wall 2 to the upper edge thereof and a lateral projection 13 at the upper end of said portion extends across the upper edge of wall 2 to which the base plate 4 is secured. The slots 11 extend from base plate 4 upwardly into portion 12 for a sufficient distance to enable the stripper plate 9 to clear the points of the pins 5 for swinging to the dot-dash position 14 in Fig. 1.

The projection 13 is adapted to form a handle for manual grasping for swinging said stripper plate and ordinarily the operator does not need to swing the stripper plate fully to the dot-dash position before the butt 6 is ejected therefrom to one side of the pin assembly including the base plate 4. The butt is shown in dot-dash lines at 15 (Fig. 1), ejected from the stripper plate and falling onto bottom 3 at one side of the pin assembly.

In the event the stripper plate 9 is released so as to fall to the position 14 seen in Fig. 1, the handle 13 will engage the side wall of the receptacle that is opposite to the extinguisher and the bent outer end portion 16 of said projection 13 will project away from the wall so engaged by the handle to facilitate engaging said handle for swinging the stripper plate back to the full line position thereof as seen in Fig. 1.

From the foregoing it is seen that the relative movement between the stripper plate and the base plate is such that a cigarette or cigar butt impaled on the pins will not only be removed from said pins but will be ejected from the stripper plate to one side of the pin assembly and ashes on plate 9 will be carried to the side of the pin assembly and will be discharged into the receptacle 1.

When the stripper plate is in the position 14 in Fig. 1, the pins and base plate are accessible for cleaning any ashes or tobacco from the top of plate 4. This operation can be accomplished without moving the receptacle by merely swinging the stripper plate to one side.

In Fig. 3 substantially the same extinguisher structure is shown as in Figs. 1, 2, but in this view the extinguisher is adapted to an ordinary table type ash tray such as the tray 20 that may be formed of ceramic material having a platform 21 projecting above the bottom 22 of the tray for supporting the base plate 23 of the extinguisher thereon. An upwardly opening recess 24 may be formed in the tray at about the juncture of the platform 21 and a side 25 of the tray for receiving a downwardly extending projection 26 along the edge of plate 23 for holding the plate in a horizontal stationary position on said platform.

The pins in this form of the invention are shown as staples that are driven through the base plate from the underside of the latter so that their legs 27 project upwardly therefrom to form the pins on which the cigar and cigarette butts are adapted to be impaled for extinguishment. The legs or pins 27 are disposed in rows in this form of the invention, the same as in Fig. 2, and the stripper plate 28 has slots therein the same as stripper plate 9, there being a slot for each row of pins. The plate 28 is pivoted to the base plate 23 for swinging from full line position in Fig. 3 to the dot-dash line position 29, in which latter position a cigar or cigarette butt on plate 28 will be ejected therefrom onto the bottom 22 at one side of platform 21.

The plate 28 has a right angle extension 30 and handle 31 thereon that are substantially the same as extension 12 and projection 13 of Fig. 1. The pins or staples 27 may be frictionally secured to the base plate or may be soldered or otherwise secured to said plate.

While the platform 21 is not absolutely essential, it is desirable inasmuch as it rigidly supports the extinguisher assembly and fills the space below the latter so that the tray may be easily cleaned.

In Figs. 1 and 3 the extinguisher assembly is po-

sitioned within the ash and butt receptacle, which is not absolutely essential, although preferable in many instances. Also in Figs. 1 and 3 the stripper plate has a right angle extension with a handle 5 thereon for swinging the stripper plate.

In the form of invention shown in Figs. 4, 5, a table tray 40 is shown having a lateral extension 41 formed thereon and projecting to one side of the tray 40 outwardly thereof (Fig. 5). A leg 42 extends downwardly from the extension 41 and supports the extension so the tray will not be apt to be upset when downward pressure is applied to the extension. Also, the leg 42 forms a vertically extending handle about which the forefinger of an operator may be curled for moving the tray from one place to another.

This extension 41 may carry the rows of upwardly projecting pins 43 that are similar in arrangement to the pins of Figs. 1 and 3.

20 A stripper plate 44 as seen in Figs. 4 and 5 is provided, said plate having a slot 45 for each row of pins. The said plate 44 is secured along the edge of the extension 41 that joins a side wall 46 of the receptacle 40 to a pivot 47 that extends at its ends through opposite side walls 49 of the receptacle 40 that adjoins the side wall 46. A handle 50 is rigidly secured to one projecting end of pivot 47 outwardly of one of the said side walls. Upon pressing downwardly on handle 50, the stripper plate 44 will be swung to dot-dash line position 52 (Fig. 5) and will clear the pointed ends of pins 43 for ejecting the cigar or cigarette butts into receptacle 40.

Upstanding opposed side walls 53 may project 35 upwardly from opposite sides of extension 41 and an end wall 54 may close the space between said side walls at their ends remote from receptacle 40 for preventing ashes from falling onto the table during the time the butts are impaled on the pins and during their removal and ejection.

Thus in the form of invention shown in Figs. 4 and 5, the handle for swinging the plate 44 is of a type that is different from the handles shown in Figs. 1, 3, and also the extinguisher assembly 15 is not within the receptacle. It is obvious, however, that the same handles as are used in Figs. 1 and 3 could be used with the plate 44 of Figs. 4, 5, and also, the extinguisher assembly of Fig. 1 could be used on the extension 41 of Fig. 5 instead of having the pins 43 secured directly to the extension 41. The provision of the extension, as shown in Fig. 5, makes possible the utilization thereof for securing the pins directly thereto. Also the slots 45 are open at their ends adjacent wall 54 and the plate 44 terminates at said wall.

From the above description it will be seen that in each form of the invention pins and a stripper plate are employed. There is relative movement 60 between the stripper plate and the pins in each form whereby the impaled cigar or cigarette butt is carried to one side of the pin assembly and is ejected from said stripper plate to one side of the said assembly.

65 It is to be understood that the pins may be stamped from sheet metal or may be cylindrical, square or of any desired cross-sectional contour as long as they have pointed free ends and are suitable for readily impaling cigar or cigarette butts thereon.

The rapid extinguishment is due to the rapid conduction of heat from the glowing end of the cigarette or cigar butt, hence it is preferable that the pins have relatively high heat conducting properties. Usually any metal will suffice.

The spacing between pins is such that the cigarette or cigar butts will not meet with undue resistance in being impaled. Usually if two or three of the pins are adapted to enter a cigarette butt impaled thereon as seen in Fig. 1, that is sufficient.

In all forms of the invention the space below the stripper plate is readily cleaned, which is a highly desirable feature inasmuch as it is impossible to keep all ashes out of this space.

I claim:

1. In an extinguisher for burning cigar and cigarette butts having a base member supporting a plurality of spaced pins vertically disposed and with their pointed ends uppermost for impaling said butts thereon, a stripper plate adapted to be positioned over said base member and formed with an opening through which said pins extend in upwardly projecting relationship relative to said stripper plate, and pivot means supporting said stripper plate and said base member for relative movement away from each other to an ejecting position in which said stripper plate is free from said pins and at one side of the latter in generally vertically extending position for stripping said butts from said pins for ejection of said butts to one side of said pins.

2. In an extinguisher for burning cigar and cigarette butts having a base member supporting a plurality of spaced pins vertically disposed and with their pointed ends uppermost for impaling said butts thereon, a stripper plate adapted to be positioned over said base member and formed with an opening through which said pins extend in upwardly projecting relationship relative to said stripper plate, pivot means supporting said stripper plate and said base member for relative movement away from each other to an ejecting position in which said stripper plate is free from said pins and at one side of the latter in generally vertically extending position for stripping said butts from said pins for ejection of said butts to one side of said pins, and an ash and butt receptacle supporting said extinguisher and positioned to receive butts ejected by said stripper plate.

3. In an extinguisher for burning cigar and cigarette butts having a base member supporting a plurality of spaced pins vertically disposed and with their pointed ends uppermost for impaling said butts thereon, a stripper plate adapted to be positioned over said base member and formed with an opening through which said pins extend in upwardly projecting relationship relative to said stripper plate, pivot means supporting said stripper plate and said base member for relative movement away from each other to an ejecting position in which said stripper plate is free from said pins and at one side of the latter in generally vertically extending position for stripping said butts from said pins for ejection of said butts to one side of said pins, and an ash and butt receptacle supporting said extinguisher and positioned to receive butts ejected by said stripper plate, said receptacle including a bottom wall spaced below said base member and to one side of the latter.

4. In an extinguisher for burning cigar and cigarette butts having a base member supporting a plurality of spaced pins vertically disposed and in a horizontal row with their pointed ends uppermost for impaling said butts thereon, and a stripper plate positioned over said base member and formed with a slot through which said pins extend in upwardly projecting relationship

thereto, said stripper plate being hinged to said base member along one edge of said base member for swinging of said stripper plate to a butt ejecting position at one side of said pins and past the pointed ends of said pins for thereby stripping said butts from said pins and ejecting them to one side of said pins.

5. In an extinguisher for burning cigar and cigarette butts having a base member supporting a plurality of spaced pins vertically disposed and in a horizontal row with their pointed ends uppermost for impaling said butts thereon, a stripper plate positioned over said base plate and formed with a slot through which said pins extend in upwardly projecting relationship thereto, said stripper plate being hinged to said base member along one edge of said base member for swinging of said stripper plate to a butt ejecting position at one side of said pins and past the pointed ends of said pins for thereby stripping said butts from said pins and ejecting them to one side of said pins, said stripper plate being swingable about an axis extending perpendicular to the direction of said slot, and a handle connected to said stripper plate for swinging the latter to said ejecting position.

6. In an extinguisher for burning cigar and cigarette butts having a base member supporting a plurality of spaced pins vertically disposed and in a horizontal row with their pointed ends uppermost for impaling said butts thereon, a stripper plate positioned over said base member and formed with a slot through which said pins extend in upwardly projecting relationship thereto, said stripper plate being hinged to said base member along one edge of said base member for swinging of said stripper plate to a butt ejecting position at one side of said pins and past the pointed ends of said pins for thereby stripping said butts from said pins and ejecting them to one side of said pins, said stripper plate being swingable about an axis extending perpendicular to the direction of said slot, and a handle connected to said stripper plate for swinging the latter to said ejecting position, and means for supporting said base member and said stripper plate on an ash and butt receptacle spaced above the bottom thereof and to one side of an ash and butt receiving portion of said receptacle which includes said bottom.

7. In an extinguisher for burning cigar and cigarette butts having a flat base plate supporting a plurality of spaced pins vertically projecting disposed and upwardly therefrom with their pointed ends uppermost and with said pins arranged in a plurality of parallel rows, a stripper plate having a flat portion adapted to be positioned over said base plate and closely adjacent thereto, said stripper plate being formed with a row of slots for said rows of pins respectively with the pins in each row projecting upwardly through one of said slots, and means hingedly securing said stripper plate along one of its edges to said base plate for swinging of said stripper plate clear of said pins about an axis extending across the ends of said slots perpendicular thereto whereby butts impaled on said pointed ends will be withdrawn from said ends and ejected to one side of said rows of pins upon so swinging said stripper plate.

8. In an extinguisher for burning cigar and cigarette butts having a flat base plate supporting a plurality of spaced pins vertically projecting disposed and upwardly therefrom with their pointed ends uppermost and with said pins

arranged in a plurality of parallel rows, a stripper plate having a flat portion adapted to be positioned over said base plate and closely adjacent thereto, said stripper plate being formed with a row of slots for said rows of pins respectively with the pins in each row projecting upwardly through one of said slots, means hingedly securing said stripper plate along one of its edges to said base plate for swinging of said stripper plate clear of said pins about an axis extending across the ends of said slots perpendicular thereto whereby butts impaled on said pointed ends will be withdrawn from said ends and ejected to one side of said rows of pins upon so swinging said stripper plate, and a handle on said stripper plate along the edge thereof opposite the edge along said axis for manual grasping to effect said swinging of said stripper plate.

9. In an extinguisher for burning cigar and cigarette butts having a flat base plate supporting a plurality of spaced pins vertically projecting disposed and upwardly therefrom with their pointed ends uppermost and with said pins arranged in a plurality of parallel rows, a stripper plate having a flat portion adapted to be positioned over said base plate and closely adjacent thereto, said stripper plate being formed with a row of slots for said rows of pins respectively with the pins in each row projecting upwardly through one of said slots, means hingedly securing said stripper plate along one of its edges to said base plate for swinging of said stripper plate clear of said pins about an axis extending across the ends of said slots perpendicular thereto whereby butts impaled on said pointed ends will be withdrawn from said ends and ejected to one side of said rows of pins upon so swinging said stripper plate, a handle on said stripper plate along the edge thereof opposite the edge along said axis for manual grasping to effect said swinging of said stripper plate, said handle being an extension of said plate formed integrally therewith, and an ash and butt receiving receptacle supporting said plates in a position for said ejection of said butts onto the bottom of said receptacle, and said handle projecting laterally outwardly from one side of said receptacle.

10. In an extinguisher for burning cigar and cigarette butts having a horizontal base plate and a horizontal stripper plate adapted to be positioned thereover and in parallel engaging relationship thereto, a row of parallel slots formed in said stripper plate, a row of spaced upstanding pins for each of said slots secured to said base plate at their lower ends and projecting upwardly through said slots, and means hingedly securing said stripper plate along one edge to said base plate for swinging about a horizontal axis adjacent one of the ends of said slots and at right angles to the latter, said means including a handle connected to the hinge for said stripper plate for manually swinging the latter.

11. In an extinguisher for burning cigar and cigarette butts having a horizontal base plate and a horizontal stripper plate adapted to be positioned thereover and in parallel engaging relationship thereto, a row of parallel slots formed in said stripper plate, a row of spaced upstanding pins for each of said slots secured to said base plate at their lower ends and projecting upwardly through said slots, means hingedly securing said stripper plate along one edge to said base plate for swinging about a horizontal axis adjacent one of the ends of said slots and at right angles to the latter, said means

5 including a handle connected to the hinge for said stripper plate for manually swinging the latter, an ash and butt receiving receptacle having side walls and a bottom wall, and means for supporting said plates adjacent one side of said walls.

12. In an extinguisher for burning cigar and cigarette butts having a horizontal base plate and a horizontal stripper plate adapted to be positioned thereover and in parallel engaging relationship thereto, a row of parallel slots formed in said stripper plate, a row of spaced upstanding pins for each of said slots secured to said base plate at their lower ends and projecting upwardly through said slots, means hingedly securing said stripper plate along one edge to said base plate for swinging about a horizontal axis adjacent one of the ends of said slots and at right angles to the latter, said means including a handle connected to the hinge for said stripper plate for manually swinging the latter, an ash and butt receiving receptacle having side walls and a bottom wall, means for supporting said plates adjacent one side of said walls, and means for swinging said stripper plate generally to the side of said base plate adjacent said receptacle for effecting discharge of butts into said receptacle.

13. In an extinguisher for burning cigar and cigarette butts having a horizontal base plate and a horizontal stripper plate adapted to be positioned thereover and in parallel engaging relationship thereto, a row of parallel slots formed in said stripper plate, a row of spaced upstanding pins for each of said slots secured to said base plate at their lower ends and projecting upwardly through said slots, means hingedly securing said stripper plate along one edge to said base plate for swinging about a horizontal axis adjacent one of the ends of said slots and at right angles to the latter, said means including a handle connected to the hinge for said stripper plate for manually swinging the latter, an ash and butt receiving receptacle having side walls and a bottom wall, and means for supporting said plates adjacent one side of said walls and spaced above said bottom wall.

14. An extinguisher for cigar and cigarette butts comprising a receptacle for the extinguished butts having a base member in the form of a lateral extension projecting outwardly from one side thereof, a horizontal stripper plate over said extension and pivoted to said receptacle for swinging about a horizontal axis generally toward said receptacle for discharge of a cigarette butt thereover onto said receptacle, said stripper plate having slots therethrough extending perpendicularly to said axes, a plurality of pins extending vertically through said slots and secured at their lower ends to said extension with the pointed ends of said pins uppermost for impalement of a lighted cigarette butt thereon, means connected to said stripper plate for swinging the latter about said axis, and a supporting member below said extension for engaging a table on which said receptacle is adapted to be positioned.

15. An extinguisher for cigar and cigarette butts comprising a receptacle for the extinguished butts having a base member in the form of a lateral extension projecting outwardly from one side thereof, a horizontal stripper plate over said extension and pivoted to said receptacle for swinging about a horizontal axis generally toward said receptacle for discharge of a cigarette butt thereover onto said receptacle, said stripper

plate having slots therethrough extending perpendicularly to said axes, a plurality of pins extending vertically through said slots and secured at their lower ends to said extension with the pointed ends of said pins uppermost for impalement of a lighted cigarette butt thereon, means connected to said stripper plate for swinging the latter about said axis, and a supporting member below said extension for engaging a table on which said receptacle is adapted to be positioned, said member being adapted to be engaged

by the finger of an operator for lifting and moving said receptacle.
